UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

AUTOMATIC PLAYER PIANO.

Application filed June 1, 1923. Serial No. 642,749.

This invention relates to automatic musical instruments such as player pianos and pertains more particularly to automatic expression mechanisms and means for governing tone intensities.

Among other objects, this invention is intended to provide apparatus capable of governing the energy used for sounding the notes of the instrument, and provides for that purpose means for obtaining very delicate adjustment thereof, and therefore precision and accuracy in tone intensities.

For purposes of illustration, the accompanying drawings show one practical embodiment of the invention; but as will appear to those skilled in the art, the invention is suitable of embodiment in various constructions and organizations other than that shown and described herein.

20 In the drawings:

Fig. 1 is a semi-diagrammatic illustration of a typical expression mechanism embodying the invention.

25 Fig. 2 is a sectional view of the improved valve construction.

Referring to the drawings, the customary striker pneumatics and valve mechanisms are shown at 1, and are connected by the striker 2 with the customary wippen 3. Any suitable 30 pneumatic construction may be used and none is therefore shown in detail.

The striker pneumatics are connected with the tracker bar T by means of the usual tracker tube 4 which may be vented to atmosphere in the usual manner by means of the opening 5. Also connected with the striker pneumatics is the wind trunk 6 which is operatively connected with the expression chest 7. This expression chest is divided into the 35 two sections 8 and 9 by a longitudinal partition as shown. The upper section 8 is connected with a suitable source of power by the wind trunk 10 and is therefore subjected to high exhaust, while the lower section 9, connected with the striker pneumatics, contains regulated exhaust as will be set forth hereafter. A passage 11 is provided between the sections 8 and 9, the effective opening of which is controlled by the valve 12. Obviously; the position of the valve 12 with respect to the passage 11, will determine playing intensities of the instrument. If the passage be restricted by the valve 12, softer tones will be played than if the opening be unre-

stricted because the air tension communicated to the player pneumatics is reduced.

Mounted on the chest 7 are valve mechanisms A, B and C similar to those shown and described in detail in Patent No. 1,409,479 of March 14, 1922. Also mounted on the chest 60 7 is the cancel mechanism D which is likewise similar to that shown and described in the above mentioned patent. These valve mechanisms are connected with the tracker bar T by tubes 63, 63^a and 63^b, and the cancel valve 65 is connected with the tracker by the tube 80. Since there is no invention in these valve mechanisms over that shown in my previous patent, they will not be described in detail herein. The valve mechanisms A, B and C 70 are operatively connected with the expression pneumatics 36, 35 and 34 by the tubes 42, 41 and 40 respectively. The fixed board 32 forms a means on which the expression pneumatics are supported, their movable leaves being secured to the board 33 which is hinged at 17 in such way as to swing vertically. The valve stem 13 passes loosely through the fixed board 32 and is connected to the movable board by suitable means. The lower end of the valve stem passes through the chest 7 and has mounted thereon the valve 12.

The operation of the expression pneumatics 34, 35 and 36 is similar to that described in Patent No. 1,409,492 of March 14, 1922 and will not therefore be described in detail. It is sufficient to say merely that the valve mechanisms and expression pneumatics are operated in such way as to cause the valve 12 to assume varying positions with relation to the opening 11, thus permitting varying quantities of air to be drawn from the regulated exhaust chest 9 through the opening 11 by the source of power. Connected to the upper end of valve stem 13 by the eye 39 is the coil spring 37 which exerts an upward pull on the valve 12. The tension of this spring may remain substantially constant or it may be varied by movement of the pneumatic 38 to which the spring 37 is connected. The pneumatic 38 is provided with a fixed leaf 44 and a movable leaf 45. A controlling valve mechanism for the pneumatic 38 is provided which may be conveniently mounted on the fixed leaf thereof. Such mechanism is here designated generally by 108 and is operatively connected with the pneumatic by one end of the passage 106, the other end of

which terminates in the valve chamber 107. This valve chamber may be provided with a port 109 to atmosphere and a port 110 to an exhaust chamber 111, which chamber may be 5 suitably connected with a source of exhaust. The valve 112, mounted in chamber 107, controls ports 109 and 110, and is operated as hereinafter described to control the degree of exhaust in the passage 106 and in the 10 pneumatic 38. This valve is governed by diaphragm 113 covering a diaphragm chamber 114. This diaphragm chamber is in turn connected with the tracker T by passage 116 connected with the tube 138 leading to the 15 tracker as shown. The valve 112 is normally held in its lower position due to the fact that the diaphragm chamber 114 is connected with the exhaust chamber 111 by the bleed 115.

The flow of air in the passage 106 is restricted by two adjustable screws 119 and 120, the screw 120 being adjusted to restrict the passage 106 less than the screw 119. A by-pass is provided around the screw 119 consisting of the passages 122 and 123; thus providing operating passages to the pneumatic 38 of two different capacities. The by-pass is controlled by a diaphragm and valve 123 superposed over the diaphragm chamber 124. This chamber is in turn connected by a passage 125 with a valve chamber 126. This chamber is provided with an opening 127 to atmosphere and an opening 128 to the exhaust chamber 111. Mounted therein is a valve 129 controlled by the diaphragm 130 superposed over diaphragm chamber 131. This chamber is also operatively connected to the tracker by means of the duct 132 and tube 139. The valve 129 is normally maintained in lowered position by the bleed 134. It will be noted, however, that valve 123 is normally maintained in raised position because the chamber 126 is normally open to atmospheric air.

When atmospheric air is admitted to the 45 tube 138 through the tracker, the valve 112 will be lifted thus opening the passage 106 to exhaust from the exhaust chamber 111. The pneumatic 38 therefore will tend to collapse, the speed of the collapse being reduced 50 however, because of the restriction imposed by the screw 119. Conversely, if the pneumatic 38 is collapsed, and the tracker opening controlling tube 138 is then closed, the pneumatic will expand slowly as atmospheric air 55 is admitted past the screw 119. If, however, while the tube 138 is open, the tube 139 be opened to atmospheric air, the valve 129 will be raised allowing suction from the exhaust chamber 111 to lower the valve 123, thus 60 opening the by-pass, and the restriction imposed by the screw 119 will be of no effect. The bellows 38 therefore will be collapsed at a greater rate of speed than before.

It is thus apparent that this valve mechanism provides two speeds of collapse for the 65

bellows 38 and is of practicable importance in obtaining crescendo effects, as has also been previously explained in Patent No. 1,409,492 of March 14, 1922.

The expression mechanisms above described operate on the valve 12 to variably restrict the opening between the sections 8 and 9, thus varying the amount of air exhausted from the player pneumatics. Since it is essential that this restriction be delicately performed in order to secure in the player pneumatics the exact degrees of tension desired, it is desirable to provide a valve which will at all times maintain a proper cooperative position with respect to its seat, or which, becoming 70 displaced, will adjust itself to proper cooperative position therewith. If the valve 12 be fixed on the valve stem 13, a slight bending or warping of the valve stem may cause the valve to seat improperly. Means are therefore provided which will permit the valve to assume a position parallel to its seat and properly hold the valve in this position.

The valve disk 20 is mounted on a spherical bearing member 21 through which there is 90 an opening 22 sufficiently large in diameter to allow the disk and bearing to be loose on the stem 13. On either side of the disk 20 are placed the collars 23 and 24, also on the stem 13, these collars being adjustably held in 95 fixed position by means of lock screws 25 and 25'. Between the collar 24 and disk 20 is placed an additional collar 26 having the opening 27 through it. The diameter of this opening is also larger than that of the valve 100 stem so that this collar may move laterally with respect to the stem. The purpose of the collar 26 is to provide a bearing circle to cooperate with the bearing circle of collar 23, and, by making the collar 26 so that it may 105 move laterally with respect to the stem, to compensate for radial and angular errors in manufacture and assembly. The adjustment of the collars is such that the valve disk 20 may be moved angularly with respect to its 110 stem, but being once moved will ordinarily retain that position.

In operation the disk 20, when lowered to a position such that it will seat, assumes a position parallel to its seat since, as explained, 115 it is held more or less loosely between the collars. If, however, the valve should become accidentally displaced from causes such as warping of the chest due to atmospheric changes, or an accidental bending of the 120 valve stem, as soon as it comes to a position of contact with its seat it is immediately readjusted to a position parallel therewith.

The practical importance of this device will be appreciated. Expression devices such 125 as herein illustrated are designed to give extremely quick and accurate regulation of tone intensities. In playing very low intensities, particularly when the valve is nearly closed, it is necessary that it should maintain a posi- 130

tion of exact adjustment with respect to its seat in order that the exact intensities may be reproduced by the player actions.

It is to be understood that this invention is not limited to the specific construction and organization described for illustration. On the contrary, the described apparatus may be variably changed, modified and reorganized without diverting from the scope of the invention as defined in the subjoined claims.

I claim as my invention:

1. A throttle valve for automatic expression mechanisms, comprising, in combination, a valve stem, a valve mounted loosely thereon having a rounded bearing surface through which the stem passes, a pair of collars fixed to said stem mounted on either side of said valve and cooperating with said bearing surface to prevent longitudinal movement of the valve relative to the stem while permitting relative angular movement therebetween.

2. A throttle valve for automatic expression mechanisms, comprising, in combination, a valve stem; a valve thereon; cooperating collar means also thereon; and means whereby said valve may move to various positions of angular adjustment with respect to said stem between said collars.

3. A throttle valve for automatic expression mechanisms, comprising, in combination, a valve stem; a valve thereon; a pair of cooperating collar means also mounted thereon; bearing means on said valve; said collars being provided with sockets in which the valve bearing rotates.

4. A throttle valve for automatic expression mechanisms, comprising, in combination, a valve stem; a valve thereon; a pair of cooperating collar means also mounted thereon; bearing means on said valve; a third collar loosely mounted on said stem between the valve and one of said cooperating collars, said third collar and one of said cooperating collars being provided with sockets in which the valve bearing rotates.

5. A throttle valve for automatic expression mechanisms, comprising, in combination, a valve stem; a valve thereon comprising a valve disk and bearing; a pair of cooperating bearing means on said stem; and means whereby one of said means may be moved laterally.

In testimony whereof, I have signed my name to this specification this 24th day of May, 1923.

CHARLES F. STODDARD.
